LESTER L. ALMOND, OF NORTH TROY, ROLLAND HERRINGTON, OF TROY, AND FRANCIS A. MATTHEWS, OF KITCHENER, ONTARIO, CANADA, ASSIGNEES TO CLUETT, PEABODY & CO., INC., OF TROY, NEW YORK, A CORPORATION OF NEW YORK

BUTTONHOLE SEWING MACHINE

Application filed July 1, 1932. Serial No. 620,444.

This invention pertains to the formation of sewed seams, and relates more particularly to a novel method of and apparatus for use in forming sewed seams in which an eye-pointed needle is used as one of the thread manipulating instrumentalities,—the present invention constituting an improvement upon the method and mechanism disclosed in copending application Serial No. 504,804, filed jointly on December 26, 1930 by Almond, Herrington and Matthews.

The invention forming the subject matter of the above application includes, among other things, the clamping of the end of the needle thread (in starting a new seam) at a point above the work and its release just before completion of the first stitch, and the employment of clamping means below the work plate arranged to grasp and hold the thread of the first stitch as it is released by the clamp above the work, the clamping means below the work operating so quickly after release of the thread end by the upper clamp that it seizes both the downgoing and the upgoing runs of the first stitch, but under some conditions does not pull the thread end down through the work as reliably as might be desired.

In accordance with the present invention the end of the needle thread is clamped above the work as the needle descends in forming the first stitch so as positively to prevent unthreading, but before the needle has risen substantially on its first upstroke, the end of the thread is released and is drawn down through the work and finally pulled out substantially straight by the action of the looper or shuttle,—or by the tension of the lower thread, and the operation of again clamping the thread at a point below the work is so delayed that only this single straight run of thread is gripped. The clamping action is thus more reliable than when it is attempted to hold two or more runs of needle thread, while by thus delaying the gripping of the thread below the work, the withdrawal of the end of the thread from above the work is made more certain.

For securing this novel action, improved mechanism has been provided which is adapt-

ed to open the upper thread-end clamp sufficiently in advance of the operation of the lower clamping means to permit the new thread end to be drawn down completely through the work before the lower clamping means is brought into action. Other features of novelty and advantage will be hereafter more fully described by reference to the accompanying drawings, wherein one desirable embodiment of the invention has been illustrated by way of example.

In the drawings,

Fig. 1 is a front elevation of a buttonhole sewing machine of a well-known type, but embodying improvements provided in accordance with the present invention, and showing the parts in the position which they occupy substantially at the end of the first stitch cycle;

Fig. 2 is a bottom plan view of the machine with the parts disposed as in Fig. 1;

Fig. 3 is a fragmentary plan view showing parts of the mechanism for actuating the clamp and cutter for the upper or needle thread,—the parts being shown in the position which they take as the needle completes its down stroke on the first stitch cycle.

Fig. 4 is a composite view, to large scale, illustrating in side elevation and in both end elevations, respectively, a guiding and supporting bracket for the clamp-actuating rod of Fig. 3;

Fig. 5 is a fragmentary bottom plan view showing the position of the clamp-controlling devices just as the needle begins to descend (or advance) in performing the first stitch cycle;

Fig. 5^a is a fragmentary section, substantially on the line 5^a—5^a of Fig. 2, showing the position of the clamp-actuating cams at the time the clamping devices occupy the position of Fig. 5;

Fig. 5^b is a view similar to Fig. 5^a, but showing the position of the clamp-actuating cams when the needle has penetrated the work far enough to make sure that it will not become unthreaded;

Fig. 5^c is a fragmentary section on the line 5^c—5^c of Fig. 2, showing the clamp latch levers in latched position corresponding to the

position of the parts illustrated in Fig. 5;

Fig. 6 is a view similar to Fig. 5, but showing the parts positioned just after release of the upper clamp-controlling latch lever 5 and the release of the upper thread end;

Fig. 6^a is a view similar to Fig. 5^a, but showing the actuating cams in the position which they occupy when the clamp-controlling devices are in the position of Fig. 6;

Fig. 6^b is a view similar to Fig. 5^b but showing the controlling cams in the position which they occupy when the needle is at the extreme end of its downward travel;

Fig. 6^c is a view similar to Fig. 5^c, but 15 showing the latch lever for the top thread clamp released from its latch, and corresponding to the position of the parts shown in Fig. 6;

Fig. 7 is a view similar to Fig. 5, but showing the parts in the position which they occupy when the needle has started on its first up-stroke, and just after the lower clamp has been actuated to seize the needle thread;

Fig. 7^a is a view similar to Fig. 5^a, but 25 showing the clamp-actuating cams in the position which they occupy just before release of the lower clamp-holding latch;

Fig. 7^b is a view similar to Fig. 7^a, but 30 showing the clamp-controlling cams in a position corresponding to that of the parts indicated in Fig. 7;

Fig. 7^c is a view similar to Fig. 5^c, but 35 showing both latch levers released, the position of the parts corresponding to that of the parts shown in Fig. 7;

Fig. 7^m is a view similar to Fig. 7, but illustrating an improved form of actuating spring;

Fig. 8 is a left side elevation of the latch-supporting lever, as viewed in Fig. 2;

Fig. 9 is a right side elevation of the lever shown in Fig. 8;

Fig. 10 is a front elevation of the bottom 45 latch lever for the upper thread clamp;

Fig. 11 is a front elevation of the latch lever for the lower thread clamp;

Figs. 12 and 13 are front and rear elevations, respectively, to large scale, illustrating the improved buttonhole produced by the 50 machine here described;

Fig. 14 is a fragmentary section substantially on the line 14—14 of Fig. 3, showing the top latch lever for the upper clamp in a 55 position corresponding to that of the parts shown in Fig. 5;

Fig. 15 is a bottom plan view of the presser foot, with certain parts removed, showing the upper thread clamp in full lines in its op-

erative or No. 2 position and in dotted lines 60 in its No. 1 and No. 3 positions, respectively;

Fig. 16 is a fragmentary section substantially on the line 16—16 of Fig. 15;

Fig. 17 is a section through the presser 65 foot substantially at right angles to the plane

of Fig. 16, but with the foot in upright position;

Fig. 18 is a perspective view, to large scale, in vertical section, showing the position of the needle and under thread clamp as the 70 needle descends in performing the first stitch cycle, the thread end being held in the upper clamp;

Fig. 19 is a view similar to Fig. 18 showing the needle as having been raised out of 75 the work and with the thread end held in the lower clamp;

Fig. 20 is a fragmentary section on a plane at right angles to that of Fig. 14 showing 80 how the thread end is clamped beneath the bed plate; and

Fig. 21 is a section similar to that of Fig. 20 but illustrating one mode of releasing the clamped thread end.

The present improvements are shown embodied in a straight buttonhole machine of the well-known Singer type, such as is disclosed in the patents to Allen No. 806,231, dated December 5, 1905, and No. 885,310, dated April 21, 1908, to which reference may 85 be had for such details of construction as are not herein fully described, it being understood that the present improvements are not necessarily restricted to this particular form of machine but may be embodied in other sewing machines intended for the same or different purposes.

Referring to Fig. 12, the numeral 100 designates the front face of a piece of fabric, for example, a shirt front, having a buttonhole 101 finished at its lateral edges with rows 102 and 103 of overseam or other suitable stitches and at its ends by the transverse or barring stitches 104 and 105. Machines of the type referred to are usually provided with means for cutting and clamping the upper thread at the completion of the stitching operation, and when a new buttonhole is to be started the clamped end of the thread leading to the needle eye remains 105 above the work during the completion of the first stitch cycle and is not usually released until after the formation of a considerable number of stitches.

The present invention provides for the certain withdrawal of the end of the upper thread T down into and preferably through to the under side of the work, giving the buttonhole a finished appearance at the front face of the fabric, as shown in Fig. 12, the upper thread end T usually appearing at 110 the rear side of the work together with the end of the under thread U, as shown in Fig. 13.

As shown in the present drawings the machine comprises the overhanging bracket arm 1 (Fig. 1) rising from the right-hand end of a bed plate 2 supported by the base 3. The 115 stitch-forming instrumentalities consist of the usual eye-pointed needle 4 carried by the 120

125

needle bar 5 mounted in the usual horizontally swinging frame and deriving its vertical reciprocating movements from a main drive shaft which has bearings in the horizontal portion of the bracket arm 1 and which is provided with the fixed drive pulley 6 and the loose pulley 7. The needle cooperates with a shuttle or other looper device mounted in a raceway 8 (Fig. 2) and carried by an oscillating shaft 9 which is actuated by means of the rocker 10 and link 11 from the main shaft of the machine. The work carrier or support comprises the longitudinally movable side plate 12 having an elongate opening 13 (Fig. 3), and the stationary throat plate P fitting within said opening and having the hole H (Figs. 18 and 19) for the passage of the needle. With this work support cooperates the presser foot 14 provided with the elongate knife opening 15. This presser foot is supported by means of a plate 16 secured to a block 17 (Fig. 1) pivotally mounted at 18 upon a block 19 carried by the slide plate 12. The plate 16 is furnished with an arm 20 (Figs. 1 and 3) projecting to the right of the pivot 18, as viewed in Fig. 1, and by means of this arm the plate 16 and the presser foot may be rocked about the pivot 18 to lift the presser foot from the throat plate.

For depressing the arm 20 there is provided a bell crank lever 21 (Figs. 1 and 3) free to turn on a shaft 22 mounted in bearings 23 projecting forwardly from the bracket 1. This bell crank lever comprises the forwardly directed arm 24 (Figs. 1 and 3) from which depends a pivoted link 24^a whose lower end is guided in an opening in a bracket 25 projecting forwardly from the bed plate 20. This link 24^a carries a bracket provided with a stub shaft on which is mounted a roller carried by a bracket 26 (Fig. 1), said roller resting upon the upper surface of the arm 20. The forward end of the lever arm 24 is furnished with an opening for the reception of a chain 27 which extends down to a treadle (not shown) actuatable by the foot of the operator to swing the bell crank lever, thereby causing the roller 26 to bear upon the arm 20, and thus rocking the plate 16 and raising the presser foot from the work.

The machine is provided with automatic stop mechanism of a usual type adapted to stop the machine automatically at the end of a certain predetermined number of stitch cycles. This stop mechanism comprises a swinging frame 28 (Fig. 1) arranged to rock in a vertical plane between pintle members 29 (Fig. 2) and normally tending to swing in a clockwise direction under the action of a spring 30 (Fig. 1). The frame 28 has slide bearings for a stop pin 31 adapted to move vertically in the frame and which is urged upwardly by means of a spring 31^a. This stop pin 31 is adapted, when the frame is

swung into vertical position, to cooperate with a stop cam 32 fixed to the main drive shaft, the cam being arranged so as first to depress the pin 31 against the action of the spring 31^a and then to permit the pin to snap up into a socket in the cam, thereby positively preventing further movement of the drive shaft, the swinging of the frame to stop position causing the belt shifter B to move the belt from the fast pulley 6 onto the adjacent loose pulley 7. The stop pin 31 has a fixed collar which, in the downward movement of the pin, is carried down below a spring-pressed pin (not shown) in a boss 22^b carried by an arm 22^a secured to shaft 22. Thus when pin 31 snaps up into the cam socket, the arm 22^a is raised, thus rocking shaft 22.

To prevent raising the presser foot during the operation of the machine, there is provided a link 33 (Fig. 1) connecting the frame 28 with a rocker member 34 disposed beneath the arm 20, and when the frame 28 is positioned as in Fig. 1, that is to say, while the machine is operating, the rocker 34 is so disposed that the arm 20 can not be depressed, but when the frame 28 is moved to stopping position, the rocker 34 is swung downwardly so as to permit depression of the arm 20.

The slide plate 12 is supported by a transversely movable slide 12^a (Fig. 1), and these plates are moved in properly timed relation by means of the usual cam 35 (Fig. 2) which is actuated through proper connections to the main drive shaft.

Referring more particularly to Figs. 3, 15, 16 and 17, the presser foot 14 is furnished with a horizontal slot 36 for the reception of the upper thread clamp and cutter. This slot is conveniently provided by making the presser foot in two parts, one of which, 14^a, is removable and which is so shaped as to provide the slot 36 between its upper surface and the opposed lower surface of the presser foot proper. The cutter 37 and the clamp 38 are secured to a vertical shaft turning in a boss 39 forming a part of the presser foot and provided at its upper end with a lever arm 40. The cutter 37 cooperates with the edge of the presser foot 14 at the end of slot 15 to cut the upper thread, while the clamp 38 cooperates with a surface 38^a (Fig. 16) above the slot to clamp the thread when the clamp and cutter are in their operative or No. 2 position, shown in full lines in Fig. 15. The surface 38^a is cut away at 38^b (Fig. 16), and when the clamp is moved to its secondary inoperative (or No. 3 position, Fig. 15) the thread is released from the clamp.

The lever arm 40 is pivotally connected to a downwardly bent portion 41 (Figs. 1 and 3) of a controlling rod or bar 42. This bar is supported and guided by a bracket 43 (Figs. 3 and 4) having spaced upstanding ears 43^a and 43^b at its opposite ends, respec-

100

95

100

105

110

115

120

121

130

- tively, said ears having openings through which the bar 42 slides. Preferably the opening in the ear 43^a is elongate to accommodate slight lateral movement of the left-hand end 5 of the bar. The bracket 43 is carried by a plate 44 (Fig. 3) secured to the left-hand end of arm 20. The rod or bar 42 is provided with a fixed collar 45 (Fig. 3) disposed at the left of the bracket ear 43^a, and with a second fixed collar 48 disposed to the left of the bracket ear 43^b. A coiled compression spring 47 encircles the rod 42, such spring being disposed between the ear 43^a and the collar 48. The compressive force of this 10 spring thus tends to move the collar 48 with the rod 42 to the right, as viewed in Fig. 3, thus tending to move the clamp and cutter to its No. 3 or thread-releasing position, as indicated in dotted lines in Fig. 15.
- 15 20 To the right of the bracket 43 the rod 42 is provided with a fixed truncated conical abutment 50 which cooperates at times with parts, now to be described, to limit movement of the bar 42 to the right.
- 25 Referring particularly to Figs. 1, 3 and 14, a detent lever 51 is mounted upon the left-hand end of the shaft 22, above described, and extends rearwardly. This detent lever is provided at its free end with a latch member 30 52 which overlies the shaft 42. This latch is pivotally supported on the end of the lever 51 to swing in a vertical plane and is furnished with a tail 53 which is normally held against stop member 54 by means of a spring 35 54^a. As thus arranged the free end of the latch may be raised without changing the position of the lever 51, but the latch can not be depressed below the position shown in Fig. 14 without corresponding movement of 40 the lever 51.
- A second detent lever 56, for determining the movement of the bar 42, is also shown most clearly in Figs. 1 and 14, this lever being pivotally supported at 57 upon a block 45 58 carried by the arm 20, the rear end of the lever being urged upwardly by a spring 56^a (Fig. 1). This lever 56 projects rearwardly from its pivot to a point slightly beyond the shaft or bar 42 and is adapted at times to 50 stand directly across the path of movement of the bar so as to limit such movement of the bar to the right. To cushion the blow of engagement of the bar 42 with the lever 56, it is preferred to provide the lever 56 with a 55 spring member 56^b (Figs. 1 and 14) at its left-hand face as viewed in Fig. 3.
- The lever 56 is provided with a downwardly directed arm 56^a whose lower end is disposed substantially opposite to a window 60 60 59 (Fig. 1) formed in the base 3. At its lower end the arm 56^a is furnished with a horizontal portion 60 upon which is mounted an elongate latch 61 adapted to swing in a horizontal plane and which is provided with 65 a spring urging it to stand substantially in the position indicated in Fig. 5 where its longest dimension is substantially perpendicular to the front face of the machine. This latch cooperates at times with a disk 63 having a smooth flat front face and a beveled edge 64. This disk is carried by a slide bar 65 guided in an opening in a bracket 66 secured to the bed plate 2 and also passing through an opening in the front flange 67 (Fig. 5) of the bed plate. A coil spring 68 (Figs. 5 and 14) surrounds this slide bar 65, bearing at one end against the bracket 66 and at its other against a pin 69 (Fig. 14) secured in the bar, the spring thus tending to move the bar 65 and the disk 63 rearwardly. 70
- The rear end of the slide bar 65 (Figs. 5, 6 and 7) lies in the horizontal plane of movement of one arm of a lever 70 pivoted at 71 and having a second arm 70^b (Fig. 10) which is engaged by the right-hand portion 80 of a spring 70^a tending to swing the lever in the counterclockwise direction, as viewed in Fig. 5. The lever arm 70 is provided with a projecting toe 72 at its right-hand end (Fig. 6) adapted to be engaged at times by a substantially spherical stud 73 projecting from the lower end of an arm 74 (Figs. 1 and 6) forming a part of the bell crank lever 21 above described, the arm 74 passing down through a suitable opening in the bed plate. Movement of the lever 21 for raising the presser foot swings the arm 74 rearwardly and thus by engagement of the stud 73 with the finger 72 swings the lever 70 to the set 90 position shown in Fig. 5, thus at the same time permitting the spring 68 to retract the disk 63 to the position of Fig. 5. In order to hold the lever 70 in this set position after the presser foot has been released by the operator, there is provided a latch member 75 (Figs. 5^c, 8 and 9) carried by a supporting lever 76 (Fig. 8) pivoted at 77 on a block 78 (Fig. 2) secured to the under side of the bed plate and urged upwardly by a spring 76^a. The latch 75 is adapted to engage the edge of the lever arm 70^b to hold the latter in set position. A second latch lever 70^c is also pivoted at 71, the lever 70^c being disposed directly below the lever arm 70^b and 100 preferably having a notch or recess 79 provided with a beveled or inclined inner wall. 105
- The lever 76 carries a block 81 pivoted at 82 and urged by a spring 83 into contact with a stop 84, the block being free to swing to the left, as viewed in Fig. 9, against the tension of spring 83, but being limited by the stop 84 against movement to the right. This block is disposed in the plane of rotation 110 of a clamp actuating cam 85 on the shuttle oscillating shaft 9. This cam has a projecting toe 86 and when the cam is oscillated in one direction, the toe 86 freely tips the block 81 and passes above it without actuating the lever 76; but when the toe 86, in turning in 115 the opposite direction, engages the top sur- 120 125 130

face of the block 81, as shown in Fig. 7^b, the lever 76 is moved down against the action of its retaining spring 76^a, thus depressing the latch 75 (Fig. 7^b) and permitting the edge of the lever arm 70^c to escape,—the beveled inner wall of notch 79 ensuring release of lever 70^c whenever latch 75 is depressed far enough to engage said surface.

The retaining lever 76 is provided with a second block 81^a (Fig. 8) adjustably secured to the lever and disposed in the plane of rotation of a second clamp-actuating cam 86^x fixed on the shaft 9, the cams 85 and 86^x being so arranged that during descent of the needle 10 the cam 85 is in advance (in the direction of rotation) of the cam 86^x. The cams 85 and 86^x have substantially the same throw or eccentricity but the block 81 is higher than the block 81^a so that engagement of block 81 15 by its cam depresses the lever 76 further than does engagement of block 81^a by cam 86^x. When cam 86^x engages block 81^a, it displaces latch 75 only enough to release lever arm 70^b, whereupon, in response to spring 70^a, the toe 20 72 of lever 70 moves quickly in a counter-clockwise direction, thus projecting the disk 63 forward to the position of Fig. 6.

The left-hand end of the lever 70^c is provided with an elongate slot 87 adapted to 30 receive a pin 88 hereinafter referred to, and when the latch 75 is displaced by action of cam 85 the lever 70^c moves over to the position shown in Fig. 7 under the action of the left-hand portion of spring 70^a. 35 The left-hand end of the lever arm 70^b is provided with a finger 87 disposed at one side of pin 88 which projects from a slide bar 89 (Fig. 2) which is guided in suitable ways carried by the bed plate. This slide bar 40 89 carries a thread-clamping member 90 (Figs. 18 and 19) arranged to reciprocate across the needle hole H in the throat plate P, and if desired may be arranged to push a bight of the lower thread U into engagement with a resilient cutting plate 91 having a sharp edge. To facilitate this action, there is provided a loop-forming arm 92 pivoted at 45 93 (Fig. 2) to a fixed part of the machine and having a slot which receives a pin 94 projecting from the slide bar 89. Thus as the slide bar is moved, the end of the arm 92 is swung rapidly so as to provide a bight of the lower thread for engagement by the end of the clamping member, and to draw 50 enough thread to start the next buttonhole.

That portion 95 of the work support which lies just to the left of the needle opening H, as viewed in Fig. 18, cooperates with the lower thread clamp 90, as hereinafter described, 55 in clamping the end of the upper thread T. For this purpose the clamp 90 is provided with an elongate opening 97 (Fig. 19) through which the needle passes when the clamp is in the position indicated in Fig. 18. 60 To permit release of the end of the upper

thread T after the first few stitches of the seam have been safely formed, the under surface of the part 95 of the plate 12 may, if desired, be provided with a transverse notch or groove 98 (Fig. 21), and as the plate 12 70 moves to the left after the seam has been started, the groove or notch 98 is brought into registry with the thread end held by the clamp, so that the end is free to be drawn 75 out of the clamp.

The operation of the machine is substantially as follows, it being assumed that the machine has nearly completed a buttonhole and is just on the point of stopping. At this time the thread clamp controlling parts 80 above the bed plate are positioned substantially as in Fig. 14, while the parts below the bed plate occupy a position substantially as shown in Fig. 2. Referring to Fig. 14, it will be noted that the latch 52 of the lever 51 is bearing against the right-hand surface of the cone 50 and is holding the rod 42 to the left against the action of the spring 47. As thus positioned the clamp and cutter for the upper thread is in its retracted, primary 85 inoperative, or No. 1 position, as indicated 90 in dotted lines in Fig. 15.

When the machine actually reaches the end 95 of the buttonhole-forming operation, the frame 28 is allowed to swing in a clockwise direction, thus moving the rocker 34 from beneath the arm 20, leaving the presser foot free to be lifted. At the same time the pin 31 is brought into the path of the cam 32, which first depresses this pin, carrying its 100 fixed abutment collar to a point beneath the snap pin in the boss 22^a on the arm 22^a; and when the stop pin 31 snaps up into the socket in the cam 32, the abutment collar lifts the pin in the boss 22^a, thus swinging the arm 22^a and turning the shaft 22 so as positively 105 to lift the lever 51, thereby removing the latch 52 from behind the cone 50. This allows the rod 42 to snap suddenly to the right, 110 as viewed in Fig. 1, until its end is arrested by the lever 56,—the blow being cushioned by the spring 56^a. This movement of the rod 42 to the right moves the clamp and cutter into the operative or No. 2 position shown 115 in full lines in Figs. 15 and 16, where the upper thread T is cut and the end leading to the needle is clamped against the surface 38^a of the presser foot. In order to remove the work from beneath the presser foot, the latter must now be raised, and the operator 120 depresses the treadle, thereby rocking the bell crank 21 and moving the link 24^a downwardly (Fig. 1) so that its roller 26 engages the arm 20 and raises the presser foot. At the same time the downwardly projecting 125 arm 74 of the bell crank 21 swings rearwardly, and its stud 73, acting against the finger 72, swings the lever 70 into the position shown in Fig. 5, causing its toe 87 to engage pin 88, thereby moving the slide 89 (upward-

130

ly as viewed in Fig. 2) and at the same time swinging lever 70° to the position of Fig. 5. This movement of the slide also swings the arm 92 so as to form a bight in the lower 5 thread and at the same time advances the clamp 90 across the needle hole in the throat plate, thereby cutting the lower thread by engagement with the sharp edge of the plate 91.

10 When the levers 70 and 70° are swung as just described, they clear the end of the latch 75, allowing the latch-actuating spring 76^a to lift the latch to the position of Fig. 5° where its vertical edge stands in the plane 15 of movement of the levers 70 and 70° so as to lock them in this set position. During this setting of the lever 70, the spring 68 retracts the disk 63, thus permitting the spring-actuated latch 61 to assume a position shown in 20 Fig. 5 wherein its length is substantially perpendicular to the face of the disk.

To start the machine, the stop frame 28 is swung over to the left by means of the usual 25 connections to a foot treadle and the belt is shifted onto pulley 6. As the needle advances in performing the first stitch cycle, it descends through the opening in the throat plate, as indicated in Fig. 18, the free end of the needle thread T still being clamped between the clamping member 38 and the surface 38^a of the presser foot (Fig. 16), it being remembered that at this time the end of the rod 42 is still in engagement with the lever 56.

35 After the needle completes its downward movement, the shuttle carries a bight of the upper thread T around the lower thread U while the needle is rising to a point above the throat plate. During the descending movement of the needle, the shaft 9 is rocked in a counterclockwise direction, as viewed in Fig. 5^a until it reaches the position of Fig. 6^b, but as the needle starts to move up, the shaft 9 begins its reverse movement. Before 40 the needle has reached the limit of its downward stroke, but after it has descended far enough to make sure that it will not become unthreaded, if the thread-end is released from the upper clamp, the cam 86^a arrives substantially at the position of Fig. 6^a, where it engages block 82^x and depresses the lever 76 just far enough to allow the lever arm 70^b to escape from latch 75, whereupon the right-hand portion of the spring 70^a (as viewed in 45 Figs. 5 and 6) immediately snaps the lever 70 back to the position shown in Figs. 1, 6 and 7, where its toe 87 comes into contact with the fixed abutment block 87^a (Fig. 7), thus limiting its further movement. This 50 movement of the lever forces the slide bar 65 forwardly, pushing the disk 63 forwardly and, by means of the latch 61, pushing forwardly the lower end of the lever 56^a. This depresses the rear end of the lever 56 to a 55 point below the rod 42, thus permitting the

latter, under the action of its spring 47, to move to its extreme right-hand position (Fig. 3). In this position the upper clamp and cutter are moved to their secondary inoperative or No. 3 position (shown in dotted lines 70 in Fig. 15) wherein the clamp 38 is positioned opposite to the recess 38^b in the presser foot, thus permitting the upper thread freely to escape from between the clamp and the presser foot. 75

The needle now begins its upward movement, and, as it rises, the action of the shuttle, or the pull exerted by the lower thread, draws the free end of the needle thread downwardly to the lower side of the work. However, before the needle has risen far enough to pull the end of the needle thread T out from the bight of the under thread U, the cam 85, which during the descent of the needle was carried past the block 81 (rocking the latter out of its path) returns to the position of Fig. 7^a where its toe 86 engages the block 81 which is now prevented from rocking by its stop pin 84. Further movement of cam 85 in the clockwise direction now forces the block 81 downwardly (Fig. 7^b) and thus moves latch lever 76 down far enough to release the lever 70° from the end of the latch 75, as shown in Figs. 6 and 7, the inclined wall of the notch 79^a in lever 70° facilitating such disengagement. The release of lever 70° from latch 75 permits the left-hand portion (Fig. 7) of spring 70^a to snap the lever 70° over to the position shown in 90 Figs. 2 and 7, thereby by means of the pin 88 moving the slide bar 89 back to the position of Fig. 1 and thus carrying the lower thread clamp 90 back to its original position. Since the upper thread has previously been carried down through the opening 97 in 95 the clamp 90, the upper thread is nipped between the clamp 90 and the under side of the part 95. The machine may now continue to form stitches, first forming the row of 100 stitches 102, then the barring stitches 104, then the second row of overseam stitches 103, and finally the barring stitches 105, whereupon the machine stops with the upper 105 thread clamped as above described. 110

During the above sequence of operations, the slide plate 12 first moves to the left, during the formation of the first row of stitches, and during this movement the bracket 43 moves to the left with its ear 43^b bearing 115 against the stop collar 48, and thus carries the rod 42 with its cone 50 so far to the left as to permit the latch 52 to ride up over the cone and to drop behind the latter. At about the same time the latch toe 61 reaches the bevel at the left-hand edge of disk 63 and slips off just as latch 52 drops behind the cone. When the latch toe 61 slips off of the disk, it allows the lever 56 to rise so that its rear end engages the rod 42, ready to jump up 120 125 130

opposite to the end of the rod when the rod has moved far enough to the left.

In making the second row of stitches the bracket 43 moves to the right, and during this movement the engagement of the latch 52 with the cone 50 prevents the rod 42 from moving to the right with the bracket. Therefore the left-hand ear 43a moves away from the collar 45 and compresses the spring 47. When the stop motion operates, the latch 52 is lifted, allowing the rod 42 to spring to the right until it engages the lever 56. At this time, the latch toe 61 is substantially parallel to the face of the disk 63. The slide plate 12 continues to move to the right until the completion of the buttonhole, whereupon the machine stops with the parts substantially in the position as described.

The machine thus automatically completes the buttonhole, cutting both upper and lower threads, and completing the buttonhole with both ends of each of the upper and lower threads extending down into or through the work. It is contemplated that other and equivalent means may be found for performing the novel process herein claimed and that changes in size, proportion and relative arrangement of parts in the mechanism disclosed may be made without departing from the spirit of the invention.

Fig. 7^m illustrates an actuator spring similar in purpose and function to the spring 70^a but so arranged that the pressures exerted upon the respective levers 70 and 70^c may be relatively varied. To this end the spring is mounted upon the rocker 100 pivotally supported on a shoulder screw 101 projecting downwardly from the bed of the machine. The rocker has a curved slot 102 concentric with the axis of the screw 101, and a set screw 103 passes through the slot for holding the rocker in adjusted position. The head end of the screw 101 projects downwardly below the rocker and forms a post about which a length of spring wire is coiled, the opposite end portions 104 and 105 of said length of wire engaging the lever 70^c and 70 respectively. The coiled portion of the wire turns freely upon the screw 101 but has a projecting loop portion 106 which bears against a stud 107 projecting downwardly from the right-hand end of the rocker, as viewed in Fig. 7^m.

With this arrangement, adjustment of the rocker 100 about the axis of the screw 101 changes the pressure exerted by the respective arms 104 and 105 upon the levers 70^c and 70, thereby permitting variation of the timing of the operation of the upper and lower clamps respectively.

We claim:

1. A sewing machine having means for holding the needle thread at a point above the work in starting a seam, means for releasing the thread end during the descent of

the needle in performing the first stitch cycle, means for pulling said end through the work, and means operative, during the next ascent of the needle, temporarily to clamp and hold the thread end at a point below the work. 70

2. A sewing machine having means for holding the needle thread end above the work, means for holding the needle thread end at a point below the work, and means operative, during the performance of the first stitch cycle in starting a seam, to release the thread end from the holding means above the work and, after an appreciable interval of time, to actuate the means below the work to cause it to grip the thread end. 75

3. Apparatus for making a sewed seam comprising an eye-pointed needle, means for advancing and retracting the needle through the work, means for holding the end of the needle thread at a point above the work as the needle advances through the work in performing the first stitch cycle, means operative to release such end before the needle completes its first advance movement thereby to permit the end to be drawn through the work, 85 and means operative subsequently to such release, but before the needle completes its next upward movement, to clamp the thread end at a point below the work. 90

4. A sewing machine having a work support, a needle, and means for reciprocating the latter, a clamp above the work support for holding the thread end as the needle descends in performing the first stitch cycle, thread-clamping means beneath the work support, and means operative at spaced intervals of time, during the first stitch cycle, to actuate the upper clamp to release the thread end and to actuate the lower clamping means to seize the thread end. 95

5. A sewing machine having a work support, a needle, and means for reciprocating the latter, a clamp above the work support for holding the thread end as the needle descends in performing the first stitch cycle, means for opening said clamp to release the thread end, a latch preventing operation of said clamp-opening means at the beginning of the first stitch cycle, thread-clamping means below the work support, means for closing said clamping means whereby to seize a thread, latch means preventing such clamp-closing means from acting at the beginning of the stitch cycle, and a pair of cams operative during the first stitch cycle to release said latch means one after the other. 110

6. A sewing machine having a work support, a needle, and means for reciprocating the latter, a clamp above the work support for holding the thread end as the needle descends in performing the first stitch cycle, spring means tending to open said clamp to release the thread end, thread-clamping means below the work support, spring means tending to close said clamping means whereby 125

to seize and hold a thread, latch means preventing both said spring means from acting as the machine starts the first stitch cycle, and cam means operative to actuate the latch 5 means during the first stitch cycle so as to permit the respective spring means to operate successively, first to release the thread end, and thereafter to clamp it below the work support.

10 7. A sewing machine having a work support, a needle, and means for reciprocating the latter, a clamp above the work support for holding the thread end as the needle descends in performing the first stitch cycle, 15 thread-clamping means below the work support, means tending, at the start of the sewing operation, to cause the upper clamp to release the thread and to cause the lower clamp to seize the thread, latch devices preventing actuation of the upper and lower clamping devices at the start of the sewing operation, and means operative successively during the first stitch cycle to retract the 20 latch for the upper clamp and subsequently to retract the latch for the lower clamping 25 means.

8. A sewing machine having a work support, a needle, and means for reciprocating the latter, a clamp above the work support 30 for holding the thread end as the needle descends in performing the first stitch cycle, a presser foot, means for lifting the presser foot, thread-clamping means below the work support, spring means for actuating said 35 clamping means, means for energizing such spring means, latch devices for retaining the upper clamp in thread-clamping position in opposition to such spring means and for retaining the lower clamping means in inoperative 40 position in opposition to the spring means, and a pair of cams arranged to act successively during the first stitch cycle to retract the respective latch devices whereby first to open the upper clamp to release the 45 thread and thereafter to close the lower clamp to seize the thread.

9. A sewing machine having a work support, a needle, and means for reciprocating the latter, a clamp above the work support 50 for holding the thread end as the needle descends in performing the first stitch cycle, thread-clamping means below the work support, and means operative during the first 55 stitch cycle to actuate said clamping means one after the other, respectively.

10. A sewing machine having a work support, a needle, and means for reciprocating the latter, a clamp above the work support for holding the thread end as the needle descends in performing the first stitch 60 cycle, thread-clamping means below the work support, and a pair of cams operative successively during the first stitch cycle to actuate said clamping means one after the 65 other.

11. A sewing machine having a work support, a needle, and means for reciprocating the latter, a clamp above the work support for holding the thread end as the needle descends in performing the first stitch cycle, 70 thread-clamping means below the work, a cam operative as the needle nears the end of its advancing stroke during the first stitch cycle to cause the upper clamp to release the thread, and a cam operative as the needle begins its return stroke during the first stitch cycle to cause the lower clamp to seize the thread.

12. A sewing machine having a work support, a needle, and means for reciprocating the latter, a clamp above the work support for holding the thread end as the needle descends in performing the first stitch cycle, 80 clamping means below the work support, means operative to release the thread from the upper clamp during the down stroke of the needle on the first stitch cycle, means for pulling the thread end down to the lower side of the work, and means for actuating the lower clamp as the needle begins its up-stroke on the first stitch cycle to seize and clamp the thread end.

13. A sewing machine having a work support, a needle, and means for reciprocating the latter, a clamp above the work support for holding the thread end as the needle descends in performing the first stitch cycle, a spring for actuating the upper clamp, said spring tending at the beginning of the sewing operation to cause the clamp to release the thread, a movable stop preventing such action of the clamp at the beginning of the sewing operation, thread-clamping means below the work support, a spring tending at the beginning of the sewing operation to actuate said clamp to seize a thread, a movable stop preventing such action of the lower clamping means at the beginning of the sewing operation, and a pair of rotary cams operative during the first stitch cycle to retract said stops successively whereby to permit said clamps to operate one after the other to release the thread and to seize it, respectively.

14. A sewing machine comprising stitch-forming mechanism including a needle, means operative during the first stitch cycle for holding the needle thread end until the needle has advanced far enough to prevent unthreading and then to release such thread end, and means operative subsequently during the first stitch cycle to seize a single run of the needle thread end at a point below the work.

15. A sewing machine comprising stitch-forming mechanism including a needle and loop-forming means, clamping means for holding the end of the needle thread at a point above the work during the first stitch cycle until the needle has nearly completed 125 130

its first down stroke, clamp opening means operative to release the thread end, and clamping means subsequently operative, during the completion of the first stitch cycle,
5 to seize a single run of the needle thread at a point below the work to prevent its withdrawal from the work.
